(57) **CLAIM**

The ornamental design for a footbed for a shoe as shown and described.

DESCRIPTION

FIG. 1 is a top, front and outer-side isometric view of a footbed for a shoe.

FIG. 2 is a front view of the footbed of FIG. 1.

FIG. 3 is a rear view of the footbed of FIG. 1.

FIG. 4 is an outer-side view of the footbed of FIG. 1.

FIG. 5 is an inner-side view of the footbed of FIG. 1.

FIG. 6 is a top view of the footbed of FIG. 1.

FIG. 7 is a bottom view of the footbed of FIG. 1.

FIG. 8 is a bottom, rear and inner-side isometric view of the footbed of FIG. 1.

FIG. 9 is a cross-sectional view of the footbed taken along line 9-9 of FIG. 6.

FIG. 10 is a cross-sectional view of the footbed taken along line 10-10 of FIG. 6.

FIG. 11 is a cross-sectional view of the footbed taken along line 11-11 of FIG. 6.

FIG. 12 is a cross-sectional view of the footbed taken along line 12-12 of FIG. 6.

FIG. 13 is a cross-sectional view of the footbed taken along line 13-13 of FIG. 6.

FIG. 14 is a top, front and outer-side isometric view of a second embodiment of a footbed for a shoe.

FIG. 15 is a front view of the footbed of FIG. 14.

FIG. 16 is a rear view of the footbed of FIG. 14.

FIG. 17 is an outer-side view of the footbed of FIG. 14.

FIG. 18 is an inner-side view of the footbed of FIG. 14.

FIG. 19 is a top view of the footbed of FIG. 14.

FIG. 20 is a bottom view of the footbed of FIG. 14.

FIG. 21 is a bottom, rear and inner-side isometric view of the footbed of FIG. 14.

FIG. 22 is a cross-sectional view of the footbed taken along line 22-22 of FIG. 19.

(Continued)

FIG. 23 is a cross-sectional view of the footbed taken along line 23-23 of FIG. 19.
FIG. 24 is a cross-sectional view of the footbed taken along line 24-24 of FIG. 19.
FIG. 25 is a cross-sectional view of the footbed taken along line 25-25 of FIG. 19.
FIG. 26 is a cross-sectional view of the footbed taken along line 26-26 of FIG. 19.
FIG. 27 is a top, front and outer-side isometric view of a third embodiment of a footbed for a shoe.
FIG. 28 is a front view of the footbed of FIG. 27.
FIG. 29 is a rear view of the footbed of FIG. 27.
FIG. 30 is an outer-side view of the footbed of FIG. 27.
FIG. 31 is an inner-side view of the footbed of FIG. 27.
FIG. 32 is a top view of the footbed of FIG. 27.
FIG. 33 is a bottom view of the footbed of FIG. 27.
FIG. 34 is a bottom, rear and inner-side isometric view of the footbed of FIG. 27.
FIG. 35 is a bottom, front and outer-side isometric view of the footbed of FIG. 27.
FIG. 36 is a top, rear and outer-side isometric view of the footbed of FIG. 27.
FIG. 37 is a cross-sectional view of the footbed taken along line 37-37 of FIG. 32.
FIG. 38 is a cross-sectional view of the footbed taken along line 38-38 of FIG. 32.
FIG. 39 is a cross-sectional view of the footbed taken along line 39-39 of FIG. 32; and,

FIG. 40 is a cross-sectional view of the footbed taken along line 39-39 of FIG. 32.
